(57) CLAIM

The ornamental design for a light with swivelling reflector and lamp, as shown and described.

DESCRIPTION

FIG. 1 is a perspective view of a front, one end and one side of a light with swivelling reflector and lamp showing the new design;

FIG. 2 is a perspective view of a back, an opposite end and an opposite side of the embodiment of FIG. 1; and,

FIG. 3 is a view similar to FIG. 1 but showing a reflector and lamp in swivelled out position.
